UNITED STATES PATENT OFFICE

NEIL D. PRESTON, OF ROCHESTER, NEW YORK, ASSIGNOR TO GENERAL RAILWAY SIGNAL COMPANY, OF ROCHESTER, NEW YORK

TRAIN CONTROL

Application filed July 23, 1923, Serial No. 653,358. Renewed March 25, 1927.

This invention relates to automatic train control systems for railroads.

In applying automatic train control to railroads, it is believed to be important to retain as far as possible the safety at present afforded by the care and vigilance of the engineer, otherwise there would be substituted the uncertain safety provided by automatic mechanism. If the vigilance of the engineer can be maintained, the ultimate safety of the train is doubly assured, because before an accident can occur, not only must the engineer fail to perform his duties, but also the automatic train control system must fail.

In accordance with the present invention, it is proposed to secure the continued vigilance on the part of the engineer by providing a suitable penalty for his neglect, the theory being that the engineer will naturally take the course of least resistance and will perform his regular duties properly rather than assume the penalty. While various methods of penalizing the engineer for his failure to take appropriate action may be employed, it is proposed to arrange a system such that a neglect or failure on the part of the engineer subjects him to some extra trouble or annoyance, making it an object for him to watch out for the indications of the block signals and obey them.

When it comes to determining the character of the automatic control to be provided, there arises the question of compromising between safety and facility of train movement. From the standpoint of obtaining a high degree of safety with the least interference with train operation, it is considered to be preferable to employ a speed control system, providing a plurality of speed limits for different points in a caution block and automatically applying the brakes in the event that these speed limits are exceeded. In the practical application of such a system to railroads, however, on account of the variation in the length of the blocks, the varied braking power and stopping distance of trains, different grades, and other conditions, it becomes difficult, if not impractical, to provide for every block and at every point in the travel of a train the speed limit which is safe

and will delay train movement to the minimum. Consequently, for certain blocks and under certain conditions, the curve or line of limiting speeds, if rigidly enforced and if the train is required to always run at speeds below this curve, will introduce serious delay.

In view of these considerations, enforcing vigilance by penalizing the engineer for his neglect and the inaccuracies of speed limiting curves, it is proposed in the present invention to make it possible for the train to run at higher speeds than required by the automatic equipment and retain vigilance by requiring the engineer to initiate, before exceeding the prescribed speed limits, an effective brake application, complete this application and maintain it so long as the speed is excessive and traffic conditions demand continued retardation of the train. It is considered to be a simple and advantageous expedient to require the engineer to manifest his alertness and vigilance by initiating a manual brake application, not only because such brake application and slowing down of the train is the best and safest thing to do under the circumstances, but also because the means by which the engineer is able to fore-stall the penalty is such that it will not be abused.

Generally speaking, this invention contemplates an organization of devices which, in the first place, will result in an automatic application of the brakes and slowing down of the train under dangerous traffic conditions if predetermined speed limits at certain points along the track are exceeded, enforcing a penalty if this automatic brake application occurs without appropriate action on the part of the engineer, and in suppressing this penalty but not interfering with the regular operation of the automatic brake applying equipment, in case the engineer is vigilant, and prior to exceeding the speed limits, initiates a brake application, and further completes and maintains such brake application until the speeds have ceased to be excessive or traffic conditions have cleared up.

While the speed limits above mentioned may be obtained in various manners, and may be continuing in their effect until changed,

for the purpose of explaining the nature of the present invention, it has been shown in connection with a speed control system of the intermittent or point-to-point type operating upon the time-distance interval principle; but it should be understood that various devices and combinations, hereinafter described, are adaptable for use with other types of speed control systems, and, in fact, 10 in various arrangements and organizations. It may be explained that the time-distance interval principle has been selected for the purposes of illustration in this particular instance, because such type is more capable 15 of adaptation or adjustment in a simple fashion to fit the varying requirements as to speed limits for the different blocks and different parts of the railroad.

In addition to the general principles and 20 underlying features of this invention, various other characteristics, advantages, and principles of operation will be pointed out hereinafter as the description progresses.

In the accompanying drawings, Figure 1 25 illustrates in a simplified and diagrammatic manner, using in many respects established conventions, the car equipment and circuits constituting this invention, also one of the track elements or inductors in its cooperative 30 position with the car-carried receiver;

Fig. 2 is a diagrammatic view showing the trackway equipment and illustrating typical speed limit curves and train performance curves; and

Fig. 3 shows a modified construction of the automatic brake application valve.

Trackway equipment.—In the form illustrated, it is proposed to communicate the desired control influences from the trackway to 40 the moving car, dependent upon traffic conditions in advance, by an intermittently acting inductive means working without physical contact through an intervening air gap, such influence communicating means 45 broadly consisting of a car-carried receiving element and track elements or inductors to cooperate therewith. The track elements or inductors have their operating condition governed in accordance with traffic conditions; 50 and while this requisite may be satisfied in various ways, and while various specific forms of control circuits for these inductors may be employed, in the typical arrangement shown in Fig. 2, the track rails 1 are divided 55 by insulated joints 2 into blocks in the usual way, one block E with the adjacent ends of two other blocks D and F. The parts and circuits associated with the various blocks are 60 in general the same; and for convenience these parts for the several blocks will be given the same reference characters with distinctive exponents. Each of the blocks is 65 provided with the usual track battery 3, and a track relay 4, the same as in ordinary block

signal systems and in conformity with established signaling practice. The system is preferably used in connection with the usual fixed signals of the block signal system; and such block signals Z are shown conventionally, without attempting to illustrate any particular form of control circuits, it being understood that these signals may be any one of the well-known or approved types and may be controlled in any one of the well-known ways.

At several points in each block are track elements or inductors T arranged in pairs. The particular point of location of these pairs of inductors and the spacing or distance between the inductors of each pair, will be more fully explained hereinafter, and for the present it is sufficient to note that a speed limit is provided at each pair of inductors depending upon the spacing of that pair. As 80 illustrated, these inductors T are located outside of one of the track rails on the righthand side of the track with respect to the normal direction of traffic, (from left to right as indicated by the arrow). Each of these track elements T comprises a U-shaped magnetic core 5 of suitable cross-section and preferably laminated, enlarged pole pieces 6, and a coil 7 on the back yoke of said core. At each pair of inductors T is a control or line relay 8; and these relays 8 of each block are connected across line wires 9 and 10 which are energized from a battery 11 when the track relay of the block next in advance is energized.

With the line relay 8 energized, the coil or winding 7 of both or the second inductor of the corresponding pair is connected in a closed circuit of low resistance including wires 17 and 18 and a front contact 16 of said line relay. It is stated here that, for the purposes of economy, the inductor of each pair first encountered by a train is preferably an iron core without any coil, only the second inductor of each pair being provided with a winding controlled by the corresponding line relay 8. It will be apparent that when a block is clear (no train in the next block in advance), the line relays 8 are energized and the second inductor T of each pair has its coil 7 closed in a circuit of low resistance; whereas if the block is a caution block due to the presence of a train in the next block in advance, the line relays 8 are deenergized, and the coil 7 on the second inductor of each pair is on open circuit.

The factors determining the location of the pairs of inductors T their effect upon the car equipment, and the significance of the curves shown in Fig. 2 can be discussed to better advantage hereafter in connection with the description of the operation.

Car apparatus.—The car apparatus shown in Fig. 1 comprises an impulse receiver R for cooperating with the track elements T. This receiver comprises a U-shaped magnetic lami-

nated core 20, with enlarged pole pieces 21, which is suitably carried on the locomotive or other vehicle in position to pass directly over the track inductors T. On one leg of 5 the core 20 is a primary winding P and on the other leg is a secondary winding S. As indicated in Fig. 1, the car-carried receiver R comes in superimposed relation to the successive track inductors T with a small air 10 gap intervening between the pole pieces of these respective devices. These track inductors and the car-carried receiver are, of course, located so as not to interfere with the trackway or rolling stock clearances; and the 15 air gap between is preferably a few inches above the top of the running rails.

The car apparatus includes a number of relays which are, of course, suitably constructed to perform their particular duties. 20 There is a primary or control relay CR connected to and controlled by the receiver R in the manner hereinafter explained; a repeater relay RR; a valve relay VR; a penalty relay P; and a check relay CK. Since these various 25 relays are carried upon the locomotive or other railway vehicle and are consequently subjected to jar and vibration, their moving parts are balanced in addition to other provisions that may be found expedient to avoid 30 false operation due to vibration. Consequently, the armatures or contact fingers of these relays are shown as of the balanced or central pivot type, biased from the horizontal to the inclined position by suitable springs or 35 the like. On account of the particular circuit arrangement employed, the repeater relay RR and the valve relay VR are provided with four contact fingers; and for the same reason the valve relay VR is shown as having two 40 windings.

Another part of the car apparatus is a time element device TE, the primary function of 45 which is to open a circuit, when operated, and maintain this circuit open for a predetermined time interval. In the form illustrated, this time element device consists of a balance wheel 22 on a freely turning shaft 23 which is biased to a predetermined intermediate position by a spiral spring 24. Fastened to the 50 balance wheel 22 is an armature 25 arranged to move into attracted position with respect to the pole piece 26 of a releasing or starting magnet 27. The shaft 23 is arranged to open and close certain contacts in different 55 positions; and for simplicity of explanation and to facilitate understanding the operation, these contacts are shown conventionally rather than in their structural form. There 60 is a contact arm 28 on the shaft 23 arranged to wipe over a stationary contact 29 after the shaft 23 has turned clockwise (as indicated by the arrow a) from the normal position shown. Another contact arm 30 engages a 65 fixed contact 31 while the shaft 23 is in the normal position and for a certain angle of

movement of said shaft near its normal position. The particular timing of opening and closing of these contacts will appear more fully hereinafter in the discussion of the operation. 70

The car apparatus of Fig. 1 also includes a suitable device for automatically applying the brakes of the train. This device may take various forms, but in the particular arrangement shown is a pneumatic valve, electrically controlled, which for convenience is designated as a whole the application valve A. This application valve A is intended to co-operate with or act upon an automatic air-brake system of the usual type and produce 75 automatically a service application of the brakes, at the same time preventing the engineer from opposing this automatic application or checking its effect. This application valve A comprises a suitable air-tight 80 casing 32, which will, of course, in practice be made in parts with suitable joining gaskets for ease in manufacture and inspection. In the casing 32 is a piston 33, with a leakage hole 85 34 therein, which is connected in the usual 90 way to a slide valve 35. The piston 33 is urged to the righthand position shown by a spring 36. The lefthand side of the piston 33 is connected to a suitable electro-pneumatic 95 valve EPV which, whenever its coils 37 are deenergized, opens and exhausts to atmosphere. This electro-pneumatic valve, which is shown in a simplified form, is constructed 100 in accordance with recognized practice, and in addition to controlling air pressure, has contacts 38, conveniently termed stick contacts, which are closed while its coils 37 are energized and are automatically opened upon deenergization thereof. The valve casing 32 on the righthand side of the piston 33 is connected 105 by pipe 39 to the usual main reservoir of the air-brake system.

The port 40 is piped to the engineer's brake valve and constitutes the sole source of supply of main reservoir pressure to the engineer's brake valve. This port 40 is open with the application valve A in the normal position shown, so that the engineer's brake valve is supplied with main reservoir pressure; but upon operation of the application valve and 110 movement of the slide valve 35 to the left, the port 40 is blanked, and the supply of main reservoir pressure to the engineer's brake valve cut off, so that the engineer can not attempt to recharge the brake pipe, while at 115 the same time he is free to exhaust the brake pipe. 120

Forming a part of the application valve A, preferably enclosed in the same casing, is an equalizing piston 41 and discharge valve 125 42 corresponding to that contained in the lower part of the regular engineer's brake valve. The underside of the piston 41 is connected at 77 to the brake pipe. The upper side of this piston is connected to a small 130

reservoir ER, preferably of the same size as the regular equalizing reservoir of the air-brake equipment; and the upper side of said piston 41 is also in communication through 5 pipe 43, cavity 44 in the slide valve 35 and pipe 45 with the brake pipe.

So long as the electro-pneumatic valve EPV is energized and closed, main reservoir pressure equalizes through the feed hole 34 on opposite sides of the piston 33, and the spring 36 overcoming friction forces said piston and the slide valve 35 to the extreme righthand normal position shown. In this position the engineer's brake valve is supplied with main reservoir pressure through the port 40, and the reservoir ER, and both sides of the equalizing piston 41 are subjected to brake pipe pressure. The other ports of the slide valve 35 are blanked.

Whenever the electro-pneumatic valve EPV is deenergized and opened, it exhausts pressure from the lefthand side of piston 33 faster than it can be supplied through the feed hole 34, whereupon the pressure on the righthand side predominates and shifts the slide valve 35 to the lefthand or operating position. In this position, the port 40 is blanked, preventing the engineer from opposing the automatic application, or releasing the brakes so long as the application valve is in this operating condition. The cavity 44 disconnects the reservoir ER and the upper side of the equalizing piston 41 from the brake pipe and connects them to a restricted exhaust port 46, which preferably has the same area as the preliminary exhaust port of the regular engineer's brake valve, assuming the reservoir ER to correspond in volume to the regular equalizing reservoir, it being understood that the size of the exhaust opening 46 and the volume of the reservoir ER have the same relation as the corresponding parts associated with the regular air-brake valve, so that the pressure in reservoir 45 ER will drop at the same rate. The cavity 47 in the slide valve 35 connects the pipe 48, leading to the exhaust of the discharge valve 42, with pipe 49 leading to a suppression valve SV hereinafter described, the pipe 49 being connected to atmosphere until the suppression valve SV has operated because a predetermined reduction has been made in the pressure of the regular equalizing reservoir, as explained hereinafter.

Referring now to the suppression valve SV, it may be explained that this device is intended to operate only if a predetermined reduction, such as twenty pounds, has been made in the normal running equalizing reservoir pressure. In other words, this suppression valve SV operates when a predetermined brake application, preferably a substantially full service application, has been made, at least so far as the equalizing reservoir is concerned. In the form shown, the

suppression valve SV comprises a casing 50 which contains a piston 51, a slide valve 52 and a spring 53. The piston 51, while provided with the usual ring to give it as tight a fit as free working will permit, also has ridges on its two faces to seat against gaskets 54 and 55 in the extreme positions of said piston. The spring 53 is preferably of such strength that it will be compressed when there is a difference of about twenty pounds per square inch on opposite sides of the piston 51, the strength of this spring depending upon the amount of reduction at which it is desired to have this device operate. The righthand side of the piston 51 on which the spring 53 acts is connected by pipe 56 to the regular and usual equalizing reservoir of the air-brake system. The lefthand side of the piston 51 and the chamber above the slide valve 52 is connected to a pressure reservoir 57 which has a connection to the brake pipe controlled by an electro-pneumatic valve 58, this connection to the brake pipe existing while said electro-pneumatic valve 58 is energized but ceasing as soon as said valve is de-energized.

The slide valve 52 has a cavity 59 therein which connects the pipe 49 leading to the application valve A to an exhaust port. With the slide valve 52 in the normal position shown, a cavity 60 connects to atmosphere a pipe 61 leading to an air switch AS. This air switch AS comprises a piston 62 urged inward by a spring 63 and a piston rod 64 carrying insulated contact members 65 and 66. The piston 62 is preferably of the trunk form shown, and when forced outward in opposition to the spring 63 seats against a gasket 67 to form an air-tight seal, so as to prevent leakage from the pipe 61.

For the purpose of controlling the suppression valve SV and also for use in connection with the operation of other parts of the car apparatus, the regular engineer's brake valve, shown diagrammatically as 69, is provided with electrical contacts opened and closed in predetermined positions of said brake valve. These contacts are shown conventionally, rather than in the way constructed for practical use, in order to simplify the explanation. There is a pair of contacts 70 which are closed only in the running position of the brake valve; another pair of contacts 71 closed only in the service (and also if desired, the emergency) position of the brake valve; and a pair of contacts 72 closed only in the release position of the brake valve.

The operation of the suppression valve SV may be conveniently discussed at this time, preparatory to a description of the operation of the complete system. With the engineer's valve in the running position and the contacts 70 closed, the electro-pneumatic valve 58 is energized by a circuit that can readily be traced on the drawing. It may be ex-

plained here that for simplicity the circuits shown in Fig. 1 have been illustrated in accordance with established convention as terminating with B and C, representing connections to the opposite terminals of a battery or other suitable source of current. With the electro-pneumatic valve 58 energized and open, the pressure reservoir 57 is directly connected to the brake pipe and the pressure 5 therein corresponds with the normal running 10 brake pipe pressure, whether that be 70, 90 or 110 pounds, and irrespective of the particular setting of the feed valve. The pressure 15 in the equalizing reservoir is, of course, the same, since the brake pipe and the equalizing reservoir are connected together when the engineer's valve is in the running position. Consequently, the pressures on the opposite 20 sides of the piston 51 are equal, and this piston is forced to and held in the lefthand position shown by the spring 53.

When the engineer moves his brake valve to the service position to make a manual brake application, the contacts 70 open, the electro-pneumatic valve 58 is deenergized and closed by its usual spring, and the normal running 25 brake pipe pressure is therefore trapped in the pressure reservoir 57. After the engineer has made a predetermined reduction in equalizing reservoir pressure, which will in time 30 result in a corresponding brake application, the pressure on the lefthand side of the piston 51, or rather the area thereof exposed within the rib on the face seated against the 35 gasket 54, becomes greater than the equalizing reservoir pressure plus the strength of the spring 53. The amount of reduction in equalizing reservoir pressure necessary to bring 40 about this condition is preferably selected to correspond with a full service application, or approximately a twenty pound reduction. As soon as the pressure on the lefthand side 45 of the piston 51 predominates, it moves to the right, the gasket seal is broken, a greater area is exposed on the lefthand side, and the piston shifts quickly to the righthand position. In the righthand position the area exposed due to the seal of the gasket 55, is reduced, and the piston is held in this position 50 with a differential of pressure large enough to assure an air-tight joint with said gasket and prevent leakage.

When the piston 51 and the slide valve 52 shift from the normal lefthand position shown to the righthand position, the pipe 61 is disconnected from atmosphere and connected to a pipe 68 leading to the main reservoir; and pressure is admitted from the main 55 reservoir to the air switch AS, forcing out its piston 62 and closing the contacts 65 and 66. This movement of the slide valve 52 also cuts off the pipe 49 from its normal connection to atmosphere.

From the foregoing, it will be observed

that the suppression valve SV is essentially a device which operates only after a predetermined reduction has been made in the normal running equalizing reservoir pressure. This reduction may take place in one or several 70 stages with no difference in the resultant effect. The action is independent of the actual value of the brake pipe pressure. This suppression valve SV, when it operates, closes certain contacts 65 and 66, and also cuts off 75 the exhaust of brake pipe pressure by operation of the application valve A.

In addition to the parts already described, the car apparatus includes a suitable speed responsive device capable of closing and maintaining closed certain contacts so long as the speed of the car is below a predetermined restricted or minimum speed limit, such as 20 miles per hour. This speed responsive device 73 is shown conventionally as being of 80 the centrifugal type suitably connected, in the manner not shown, to the car wheels and acting to close contacts 74 when the speed of the car is below said minimum speed.

In conformity with the principles herein-before stated, it is proposed to penalize the engineer for his failure to take appropriate action; and in the particular form of the invention illustrated, this penalty is provided by requiring the engineer after his failure, to operate a reset switch RS. This reset switch RS is preferably located so as to be accessible only from the ground, so that the train has to be stopped before said switch can be operated. This reset switch RS may, if 90 desired, be located in a locked or sealed box or equipped with a recorder. In the simplified form shown, this reset switch RS comprises two switch arms 75 and 76 operated simultaneously from the normal position 95 shown in full lines to the dotted position. By reason of the electrical connections, this reset switch can not be fastened in its resetting position without detection, since the brakes can 100 not be released to permit the train to proceed 105 with the reset switch in its operated position.

Operation.—The operation of the system of this invention is more conveniently taken up in steps first and then the operation as a whole under the operating conditions encountered in practice briefly summarized.

The impulse communicating means operates in the following manner. The primary coil P of the car receiver R is normally energized by a circuit which may be readily traced 120 on the drawing, this circuit including a check relay CK so as to detect failure of the supply of sufficient current to said primary coil to assure satisfactory operation. The secondary coil S is connected in series with a normally energized stick circuit for the relay CR as follows:—commencing at C, secondary coil S, wire 80, relay CR, wires 81 and 82, front contact and armature 83 of said relay to B. When the receiver R passes over a 130

track inductor T having no coil or with the coil on open circuit, there is a change in the flux produced by the primary coil P through the secondary coil S, producing an induced voltage, first in one direction and then in the other, which acts to deenergize the control relay CR. As soon as the armature 83 of the relay CR is retracted, its normally closed stick circuit is broken; and consequently even through the induced voltage in the secondary coil S is only momentary, the relay CR remains deenergized.

If the coil 7 of the track inductor T is closed at the time the receiver R passes over said inductor, this coil acts to oppose or choke back the passage of flux through said inductor, with the result that the voltage induced in the secondary coil is much reduced and is insufficient to cause operation of the armature of the relay CR.

Thus, each time the car passes an inductor without a coil or having its coil on open circuit, the control relay CR is deenergized and remains deenergized until otherwise restored, but if the coil 7 of the track inductor is on closed circuit, the relay CR is not operated.

Speed limits.—Each pair of track inductors acts to produce a control upon the car dependent upon the speed of the car at this control point. This speed limit depends upon the spacing of the inductors of the pair and is due to the following operation of the car-carried relays and the time element device.

When the car passes the first inductor, and the control relay CR is deenergized, a normally closed stick circuit for maintaining the repeater relay RR energized is interrupted, this circuit being traced as follows:—commencing at B, armature of the relay RR, its contact finger 84 and front contact, wires 85 and 86, relay RR, wire 87 and insulated front contact 83^a of relay CR to C. The deenergization of the relay RR causes its armature and contact fingers to shift to the position indicated by the dotted lines, resulting in the opening of said stick circuit at the finger 84 and the opening of two normally closed circuits, one for the releasing magnet 27 of the time element device, and the other the stick circuit for the upper winding of the valve relay VR. The circuit for the releasing magnet 27 thus interrupted may be readily traced on the drawing to the finger 87 of the relay RR. The stick circuit for the valve relay VR may be traced as follows:—from B through finger 88 of the relay RR, wire 89, upper winding 90 of relay VR, wire 91, front contact and finger 92 of relay VR to C. At the same time that this stick circuit for the valve relay VR just traced is broken, an alternative stick circuit is established as follows:—from B to the finger 93 and back contact of relay RR, wire 94, normally closed contacts 30—31 of the time element device TE, wire 95, lower winding 96 of relay VR.

wires 97 and 98, front contact and finger 99 of relay VR to C. The contact fingers 88 and 93 are preferably so constructed that the last traced stick circuit is made before the circuit through the winding 90 is broken; or in other words, the front and back contacts 88 and 93 of the relay R are make-before-break contacts.

Upon deenergization of the repeater relay RR, a pick-up circuit for the main control relay CR is established, from B through the finger 88 of the relay RR and its back contact, wires 100 and 81, relay CR, wire 80 and secondary coil S to C. After the control relay CR has been reenergized, and also after the shaft 23 of the time element device has turned through a few degrees from its initial position, the pick-up circuit for the repeater relay RR is established:—commencing at B, contacts 28—29 of the time element device, wires 101 and 86, relay RR, wire 87 and insulated fingers 83^a of the relay CR to C. The contacts 28—29 are so arranged as to close long enough before the contacts 30—31 open to permit the relays CR and RR to pick up their armatures. As soon as the relays CR and RR are again energized, they are maintained energized by their stick circuits heretofore traced, and similarly the valve relay VR has its winding 90 maintained energized so that subsequent opening of the contacts 30—31 of the time element device produce no effect.

From the foregoing explanation, it can be seen that the organization of circuits including the valve relay VR is such that, upon the reception of the first impulse from the trackway at the first inductor, the parts being in the normal condition, this valve relay is maintained energized; and except for the starting of the time element device, no change has been effected in the car apparatus.

Upon passing the second inductor of a pair, in its active stopping condition, the effect upon the car apparatus depends upon the speed of the train. In the first case, if the speed of the train has been below the prescribed limit, there has been time enough for the balance wheel 22 of the time element device to return to its initial position shown and be locked by the magnet 27, before the control relay CR is deenergized at the second inductor. Consequently, at the time the control relay CR drops, the relay RR is energized and the time element device is normal, so that the same cycle of operation as hereinbefore described takes place with no effect upon the valve relay VR and merely starting another operation of the time element device.

In the second case, if the speed of the train is above the prescribed speed limit, then the time taken by the train in traveling from the first inductor of the pair to the second inductor is less than the time interval for which the time element device is set; and at the

instant the control relay CR is dropped by the second inductor, the time element device will not have returned to normal and contacts 30-31 in particular will be open. Referring to the effect of the second impulse, the control relay CR and the repeater relay RR are dropped the same as before; but when the relay RR drops, the valve relay VR also drops, because the contacts 30-31 are open. Once the valve relay VR is deenergized, it remains deenergized, the circuits through both of its windings 90 and 96 including front contacts 92 and 99 which are opened upon deenergization of this relay. Upon making of the contacts 28-29 during the return swing of the balance wheel 22, the relay RR is energized, the control relay CR having been previously energized through the back contact 88 of said relay RR. The energization of the relay RR supplies current again to the magnet 27 which catches and holds the balance wheel 22. Thus, the relays CR and RR and the time element device are restored to the normal position; but the valve relay VR, due to the excessive speed, has been deenergized.

Enforced penalty.—As previously explained, it is the purpose of the system of this invention to maintain vigilance on the part of the engineer by enforcing a penalty in case he fails to take the appropriate action at the right time. In this particular instance, the action required of the engineer to forestall or prevent the penalty consists in initiating a manual brake application by placing the regular engineer's brake valve in the service position. Obviously, the engineer will not have to keep alert if he may take this action after the automatic control has taken effect; and vigilance on the part of the engineer is assured only if he is required to act prior to the automatic operation, specifically that automatic operation represented by the deenergization of the valve relay VR or the equivalent condition manifesting excessive speed. If the engineer fails to take timely action in this manner, he is penalized. In this instance, the penalty consists in requiring the engineer to operate the reset switch RS in order to proceed. If this reset switch RS is accessible only from the ground and the train must be stopped before it can be operated, it will be readily appreciated that the engineer has been subjected to some annoyance and some publicity, and is penalized to that extent. If an automatic register is connected to the reset switch RS, it would be possible to ascertain whether or not the engineer was neglectful, and he could be disciplined accordingly.

To explain the operation of enforcing a penalty, in accordance with the specific embodiment shown, assume first that the engineer is alert and moves his brake valve handle to the service position prior to the

deenergization of the valve relay VR. This closes an energizing or pick-up circuit for the penalty relay P as follows:—commencing at B, contacts 71 on the engineer's brake valve closed only in the service position, wires 102 and 103, relay P, wires 104 and 105, front contact and finger 106 of the valve relay VR to C.

The penalty relay P, once energized, is maintained energized irrespective of the deenergization of the valve relay VR, by a stick circuit as follows:—commencing at B, contact 71 on the engineer's brake valve, wires 102 and 103, relay P, wires 104 and 107, front contact and the contact finger 108 of relay P to C.

It will be evident that the engineer must keep his brake valve in the service position to maintain the penalty relay energized, at least until a predetermined reduction in equalizing reservoir pressure has been made and the air switch AS has operated to close its contacts 65, these contacts with their connection to B forming with wire 109 an alternative or multiple path for the contact 71 and wire 102. Consequently, after the predetermined reduction has been made in equalizing reservoir pressure, the engineer may move his brake valve out of the service position to the lap position and avoid useless over-reduction in the pressure of the equalizing reservoir and brake pipe.

The net result of the initiation, completion, and maintenance of a full service application manually by the engineer prior to the deenergization of the valve relay VR is the energization of the penalty relay P, it being possible with the relay P energized to automatically reset the valve relay VR in the manner hereinafter explained.

Assume, however, that the engineer is asleep or otherwise neglectful of his duties and fails to make timely operation of his brake valve. As soon as the valve relay VR is deenergized, the opening of its front contact 106 prevents subsequent energization of the penalty relay P, with the result that this valve relay VR can only be restored by operation of the reset switch RS.

Upon operation of the reset switch RS, an energizing circuit for the lower winding 96 of the valve relay VR is established as follows:—commencing at B, contacts 74 of the speed-responsive device 73 closed because the train is at rest, wires 110 and 95, winding 96, wires 97, 111 and 112, reset switch contact 76 and its back contact to C. After the valve relay VR has been reenergized in this fashion, it is kept energized subject to the automatic control due to excessive speed in the same manner previously explained. It will be noted that whenever the reset switch RS is operated to move the contact 76 to the closed position, the contact 75 mechanically connected thereto is simultaneously moved to the open position, in-

interrupting the energizing circuit for the electro-pneumatic valve EPV. In short, so long as the reset switch RS is in its operative or resetting position, the electro-pneumatic valve EPV is kept deenergized and the brakes applied; and hence the reset switch can not be carelessly or maliciously left or fastened in the resetting position and defeat the operations of the invention, particularly in avoiding a penalty.

Automatic brake application.—Each time the valve relay VR is deenergized, a normally closed stick circuit for the electro-pneumatic valve EPV is opened, this circuit being as follows:—commencing at battery B, front contact 113 of check relay CK, wire 114, winding 37 of the EPV, wires 115 and 116, normally closed contacts 38 of said EPV, wires 117 and 118, reset switch contact 75, wire 119, front contact and finger 120 of the valve relay VR to C. The electro-pneumatic valve EPV remains deenergized so long as the valve relay VR is deenergized.

The deenergization of electro-pneumatic valve EPV results in operation of the application valve, as already explained, to produce an automatic application of the brakes. The venting of the brake pipe by the application valve A continues until the slide valve 52 is shifted, that is, until the engineer has manually made a predetermined reduction in equalizing reservoir pressure. When this latter condition exists further venting of the brake pipe by the equalizing piston discharge valve 42 is unnecessary. Even though the brake pipe pressure may not have actually been reduced to the desired extent at the instant the cut off of the brake pipe exhaust at cavity 59 takes place, it is assured that the desired reduction in brake pipe pressure will inevitably occur in time, inasmuch as equalizing reservoir pressure has been reduced by the engineer's brake valve. The limitation in the amount of reduction in brake pipe pressure upon automatic operation of the application valve A is determined by the action of the engineer in effecting manually an equivalent reduction; and if the engineer is incapacitated or fails to make any reduction in equalizing reservoir pressure, it would at first appear that there is no automatic over-reduction, due to the fact that the pressure in the reservoir ER continues to drop and the exhaust from the brake pipe through slide valve 52 continues only until the pressures in the brake pipe and the equalizing reservoir, which are connected together with the engineer's valve in the running position, have dropped to the point where the slide valve 52 shifts, but this is not true, because with the engineer's brake valve in the running position the valve 58 is energized and the pressures on opposite sides of piston 51 are equal, leaving the valve 52 in its normal position so that the brake pipe is entirely vented when the valve EPV is de-

energized with the engineer's brake valve in the running position.

Under ordinary conditions, the engineer will have placed his valve in the service position and commenced reducing the equalizing reservoir pressure before the application valve A operates, this assuming that the engineer, due to the penalty, remains alert and puts his brake valve in the service position before the valve relay VR drops. Consequently, under ordinary conditions further exhaust of brake pipe pressure, due to the automatic operation of the application valve A, is cut off as soon as predetermined reduction has been made in equalizing reservoir pressure.

It will be noted that the port 40 of the application valve A, connecting main reservoir pressure to the engineer's brake valve, is closed when the application valve operates. This prevents the engineer from opposing the automatic application or releasing or recharging after such automatic application has taken place. In short, the brakes are applied and remain applied until the electro-pneumatic valve EPV is reenergized.

It will also be observed that in those cases where the engineer is vigilant, the automatic operation of the application valve, taking place while the engineer's valve is in the service position and equalizing reservoir partly reduced, brings about venting of the brake pipe at two places, at equalizing piston discharge valve 42 and equalizing piston discharge valve in the bottom of the regular engineer's valve. On account of the use of the pistons and a restricted rate of discharge of the pressure in the reservoir ER, this venting of the brake pipe at two places does not end to give a quick action or emergency, because the rate at which the pressure falls in the reservoir ER and in the regular equalizing reservoir is the same, and the equalizing pistons and their discharge valves act automatically in the well-known manner to prevent the brake pipe pressure falling at a greater rate.

The electro-pneumatic valve EPV can not be reenergized until the valve relay VR has been picked up, this being accomplished by manual reset as already explained or by automatic reset to be hereinafter explained. Because the valve relay VR may be automatically reenergized, and because it is undesirable to have an automatic release of the brakes, stick contacts are provided for the electro-pneumatic valve EPV and a shunt therefor, comprising wires 121 and 122 and contacts 72 on the engineer's brake valve closed in the release position. By virtue of this arrangement, the electro-pneumatic valve EPV is not automatically energized but only as a result of a deliberate act on the part of the engineer, namely, movement of his brake valve handle to the release po-

sition. There must be an actual movement of the valve handle by the engineer, otherwise there can be no automatic reenergization of the electro-pneumatic valve EPV. 5 The contacts 72 are disclosed as being closed in the release position only, because the engineer in releasing the brakes ordinarily makes this movement; but it is obvious that separate push buttons, or contacts closed in other positions of the engineer's brake valve 10 may be employed, if desired.

In connection with the operation of avoiding a penalty, and also limiting the amount of reduction upon automatic operation of the 15 application valve, the engineer is obliged, as already explained, to keep his brake valve in the service position until a predetermined reduction, say twenty pounds, has been made in the equalizing reservoir pressure, the slide 20 valve 52 has shifted and contacts 65 are closed. As an aid to the engineer to facilitate the manipulation of his brake valve and permit him to move it from the service position to the lap position as soon as the desired 25 reduction has been made, a suitable signal, preferably an audible signal, such as the bell 123, is provided, and this signal is operated by the closing of contacts 66 when the air switch AS operates. The bell 123 is pref- 30 erably of the single stroke type. With the aid of this signal, the engineer is able to place his brake valve in the service position, and without particular attention to time or watching the gauges, is able to tell the very instant 35 it is permissible for him to lap his valve without incurring a penalty. Whenever the electro-pneumatic valve EPV is reenergized after operation of the application valve A, the pressure builds up on both sides of the piston 40 33 and the slide valve 35 is returned to the normal position shown, opening port 40 so that the brakes may be released and connecting up the reservoir ER again with the brake pipe. It may be explained here that the cavity 45 47 is provided to avoid brake pipe leakage in case the discharge valve 42 should not seat tightly.

Automatic reset of valve relay VR.—It has been explained how the valve relay VR may be manually reset by operation of the reset switch RS. This relay VR may also be automatically reenergized in two different ways, one by the action of the track inductors, and the other by the closing of the speed contacts 55 74.

The inductors T are arranged in pairs as shown in Fig. 2, and the first inductor of each pair has no winding so that it is always able to drop the control relay CR. Upon dropping of the control relay CR, the repeater relay RR is likewise deenergized. Assuming the time element device TE to be in the normal condition, and further assuming that the engineer has been vigilant and that the pen- 60 65 alty relay P is energized, then the valve relay

VR may be reenergized by a circuit that may be traced as follows:—commencing at B, contact finger 93 and back contact, wire 94, contacts 30 and 31 of the time element device, wire 95, lower winding 96 of relay VR, wires 70 97, 111 and 124, contact finger 108 of the penalty relay P and its front contact to C.

Thus, at the first inductor of each pair, the valve relay VR is reenergized, momentarily at least. Having fixed this in mind, it is next in order to consider the conditions under which the valve relay VR will remain energized. In the first place, this relay VR will be deenergized at the second inductor of the pair if the speed is excessive, for the same 75 reasons hereinbefore explained. In the second place, if the second inductor of the pair is in the inactive or non-stopping condition, due to the connection of its coil 7 in a closed circuit of low resistance, then the valve relay 80 VR likewise remains energized. If the speed of the train has been reduced below the safe permissible limit, the valve relay VR is energized and kept energized; and likewise, if traffic conditions have cleared up since the 85 valve relay VR was deenergized, then this relay is energized and kept energized at the 90 next pair of inductors encountered by the vehicle.

Separately and independently of the inductor control just explained, the valve relay VR may be energized, providing the engineer has been vigilant and the penalty relay P is picked up, as soon as the speed of the train has been brought below some predetermined minimum speed, such as twenty miles 95 per hour, and the speed contacts 74 close. The energizing circuit for the relay VR in this instance is from B through contacts 74, wires 100 110 and 95, and through the lower winding 96 and the front contact of the penalty relay, the same as in the circuit just traced. The particular purpose and advantage of restoration of the valve relay VR at low speeds 105 will be pointed out more fully hereinafter.

Summary of operation.—For the sake of simplicity and convenience, the operations of the various devices and circuits constituting the system of this invention have been discussed more or less separately and independently. A full appreciation of the advantageous features and the whole scheme of operation is best obtained by briefly summarizing the actions and operations in connection with automatic train movement in automatic block signal territory; and for this purpose there is shown in Fig. 2 a typical layout of inductors and curves to facilitate explanation of the train movement.

Referring to the curves of Fig. 2, the curve 125 130 is a speed-distance curve representing the speeds at the various points in the block E at which an application of the brakes must be initiated in order to bring the train to a stop at the end of this block. This curve 130

130 is not intended to be exact, and of course varies with the character of train braking equipment.

Generally speaking, this curve 130 is a "dead-line" or limiting curve of speeds which, under the particular conditions assumed, can never be exceeded by a train without there being immediately initiated an effective brake application, assumed to be a full service application. The maximum speed at which the train may pass the signal at the end of the block E is assumed to be twenty miles per hour. The last pair of inductors TP^2 in the block E, traffic being from left to right as indicated by the arrow, is spaced so as to prescribe a speed limit of twenty or twenty-two miles per hour. The location of this last pair of inductors TP^2 is arbitrarily selected with due regard to the varying factors to afford the desired facility of train movement consistent with safety. The point where the line 131, projected upward from the second inductor of the pair TP^2 cuts curve 130, gives the proper speed limit for the next pair of inductors TP^1 in the rear, the probability of a train accelerating between pairs of inductors being disregarded for the sake of simplicity. The location of the intermediate pair of inductors TP^1 is arbitrarily determined, but its spacing is such as to provide the speed limit as just stated. Similarly, the point where the line 132, projected vertically from a second inductor of the pair TP^1 , cuts the curve 130, determines the speed limit for the first pair of inductors TP , which may be located arbitrarily as shown.

It should be understood that this particular arrangement of pairs of inductors and this particular scheme for determining the spacing of these inductors and their location is susceptible of considerable variation, and the present discussion is designed principally to facilitate explanation of the present invention without explaining in detail the characteristics of the time-distance interval system of speed control, this system of speed control by itself forming no part of the present invention.

Assuming an arrangement and location of pairs of inductors, as just described, there are then three different speed limits indicated by the arrows 133, 134 and 135 which the train can not exceed at these particular points without an automatic operation of the car equipment constructed in accordance with the time-distance interval systems of speed control. So long as the speed of the train is always below these speed limits, the valve relay VR of Fig. 1 is maintained energized, and there is no automatic brake application, nor need for the engineer to make a manual brake application. In order to keep below these speed limits, however, the train must run something as indicated by the perform-

ance curve 136, and it will be noted that this is at much lower speeds than is actually demanded by safety, the several safe speeds being represented by the curve 130.

Moreover, in order to bring the speed of his train below the speed prescribed by the first pair of inductors TP and indicated by the arrow 133, it is necessary for the engineer, particularly on down grades, to start his brake application at some distance back of the first pair of inductors TP , with the result that, if this brake application is not made until the signal at the entrance to the block E is actually passed, the brakes will be automatically applied at the first pair of inductors TP .

Assume now that the block E is a caution block, all inductors being active, and assume that the engineer is alert. The automatic operation (which of course varies under different conditions), will be something as follows:—with the engineer observing signal Z at the entrance to the block E at caution and realizing that this train is running at high speed (which is assumed to be the case, rather than at speeds below the inductor speeds), moves his brake valve to the service position before passing the first pair of inductors TP , at least, before deenergization of the valve relay VR . The penalty relay P is energized and maintained energized. If the engineer has made a predetermined reduction in equalizing reservoir pressure, guided by the signal 123, he may lap his valve and avoid over-reduction.

When the train passes the first pair of inductors TP , the speed being excessive, the valve relay VR is deenergized and the application valve is operated. As soon as the desired reduction has been made in equalizing reservoir pressure by the manual action of the engineer, venting of the brake pipe by the application valve A is arrested. The application valve A, however, always operates at each pair of inductors, if the speed is excessive, irrespective of what action may have been taken by the engineer. The train now slows down, due to the brake application which may be said to be partly manual and partly automatic, or a manual application accompanied or followed up by an automatic application. The engineer can not release the brakes because the slide valve 35 of the application valve A cuts off main reservoir pressure. The train continues with the brakes applied and in time would stop before reaching the end of the block.

Imagine now that the train, with the application valve operating, and the penalty relay energized, passes the second pair of inductors TP^1 and suppose that danger conditions in the block ahead still exist and the second inductor of this pair is still active. The impulse from the first inductor, the time element device TE having in the meantime returned

to the normal position, automatically reenergizes the valve relay VR. This, however, does not cause release of the brakes. In the first place, the electro-pneumatic valve EPV 5 will not be energized unless the engineer's valve is in the release position; and in the second place, even though energized, there would not be time to restore the application valve A and accomplish anything in recharging 10 the brake pipe before passing the second inductor of the pair, a matter of a second or two.

If the speed of the train is still above the inductor speed, as indicated by the curve 137, the valve relay VR is immediately deenergized, 15 and the braking conditions continue. If, however, it should happen that the train, being especially well braked or in exceeding the inductor speed 133 by very little, should pass the second pair of inductors below the speed 20 limit 134 prescribed thereby, the time element device TE will have returned to the normal position before the relay RR drops for the second time; and the valve relay VR remains energized, permitting the engineer to energize 25 the electro-pneumatic valve EPV by moving the brake valve to the release position, and resulting in the release and restoration of the application valve A and the suppression valve SV.

Suppose, however, that by the time the train in question reaches the second pair of inductors, the block in advance has become unoccupied. Then, the winding on the second inductor of the pair TP¹ is on closed circuit and no impulse is communicated thereby. The valve relay VR is restored by the first inductor as before, and inasmuch as no second impulse is received, this relay VR remains energized, permitting release of the 40 brakes, irrespective of what the speed may be. In other words, if traffic conditions in the block ahead clear up, the following train is automatically released at the first pair of inductors it thereafter passes and is permitted 45 to accelerate immediately, providing a safe and efficient form of intermediate release in a caution block ordinarily not possible with a system of train control employing intermittently acting impulse communicating 50 devices.

If the block is still a caution block at the time the train passes the second pair of inductors TP¹, the brakes must be kept on, as previously explained. An automatic release 55 and restoration of the valve relay VR would be possible at the third pair of inductors TP² in case that the conditions have in the meantime cleared up, or the speed has been reduced below the minimum speed. It may 60 happen, however, that a train would pass the last pair of inductors TP² in the block E above the speed limit 135 prescribed by these inductors; and in this event, there would be no automatic release, the brakes would have 65 to be kept on, and the train would be brought

to a stop. Also, the braking conditions, the inductor speed limits and other varying factors may be such that a train may be stopped after passing the second pair of inductors and before reaching the third pair, if a full service application of the brakes is maintained. In order to avoid any of these contingencies which would compel a train to stop, rather than permitting it to proceed, the speed contacts 74 are provided, so that whenever the speed of the train has been reduced below a predetermined minimum value relay VR is reset, provided of course the engineer has been vigilant.

As already fully explained, the engineer must watch out for the indication of the block signals and recognize the excessive speed and act before the automatic apparatus acts to deenergize the valve relay VR, otherwise the engineer is penalized by being required to stop and operate the reset switch RS. In other words, the engineer can not disregard the block signals or pay no attention to his speed and wait until the automatic train control apparatus has operated, and then act. This, it is believed, is an essential and important characteristic of any arrangement for enforcing vigilance on the part of the engineer. The engineer should derive all information as to how and when to slow down his train from his own observation of the signal indications and from his own realization of excessive speed; and it should not be possible for him to wait until there is a signal, sound, or until he feels the brakes being applied, before he is required to take the appropriate action to avoid the penalty.

As previously explained, the audible signal or bell 123 is provided to assist the engineer and advise him when he may lap his engineer's valve. Since the brakes once applied must be kept on until the electro-pneumatic valve EPV has been reset, it is desirable for the engineer to know when this has happened and it is proper for him to release the brakes. For this purpose there may be added, if desired, a suitable visual or audible signal under the control of the valve relay VR, so that the engineer may know as soon as this valve relay VR has been reenergized, and may then move his regular brake valve to the release position and reenergize the electro-pneumatic valve EPV. The addition or adaptation of such a signal to the specific embodiment shown, being a matter of choice or preference and being obvious has not been illustrated.

In addition to enforcing restricted speed limits on account of the presence of other trains ahead, it is often desirable to require reduced speeds, irrespective of traffic condition, at certain places along the railroad where the so-called fixed hazards exist. For example, sharp curves, down grades, yard limits, crossings, and other permanent haz-

ards along the railroad make it desirable to enforce a reduced speed limit at these particular places. In accordance with the type of speed control herein illustrated, such restrictions upon the maximum speed of the train at various points under clear traffic conditions are accomplished by a pair of permanently active inductors located at the desired point and spaced the appropriate distance apart. Such a pair of inductors TM are illustrated in Fig. 2 near the end of the block D. Both of the inductors of this pair are without coils or windings 7, and both always act upon the car apparatus, irrespective of the presence or absence of other trains, to cause an automatic brake application if the speed of the train at this particular point exceeds the predetermined limit desired and prescribed by the spacing of the inductors. According to the present invention, the engineer must recognize the existence of these limited speed zones or control points, the same as for a caution block; and if the speed of the train is above the prescribed limit, the engineer must initiate a brake application in the same way already described, in order to avoid the penalty. The provision of this suppressed penalty feature, characteristic of this invention, serves to facilitate train movement at these points of restricted speed, as well as at the control points in a caution block. To illustrate, referring to Fig. 2, assuming that, on account of the permanent hazard near the signal Z, it is desired to have a restricted speed at the signal, say 40 miles per hour. The permanently active pair of inductors TM must, then, be located a distance back of the signal Z sufficient to bring the train from its possible normal running maximum speed, say 60 miles per hour, to 40 miles per hour. In other words, the speed limit prescribed by the inductors TM must, in the interests of safety be 40 miles per hour or even less if acceleration is to be taken into consideration, even though this 40 miles per hour speed is not necessary until the signal is reached. Without the expedient of suppressed penalty of this invention, and with the system of the type in which a penalty is imposed whenever an automatic brake application occurs, it can be seen that the engineer is required to reduce speed much sooner than really necessary, being 40 miles per hour at the inductors TM, although not necessary to be at this speed until reaching the signal. With the present invention, however, the engineer may proceed at the regular normal running speed up to the inductors TM, and then if vigilant and realizing the need for reduced speed, the engineer may initiate a brake application, avoiding the penalty by so doing, and eventually bringing his train to the desired intermediate speed by the time the point for such restricted speed is reached.

68 In a particular arrangement selected as a

typical illustration and shown in Fig. 2, it is assumed that the first inductor of the pair TP will serve to reset the valve relay VR, after deenergization thereof at the pair of inductors TM, making it possible for the engineer to release the brakes after having brought the speed of the train down to the desired extent. This particular arrangement, however, is merely illustrative, and it should be understood that, if necessary, a special single inductor may be located at the appropriate point in advance of a pair of permanently active inductors to reset the apparatus after the desired speed limit has been enforced. Incidentally, it should also be understood that the pair of permanently active inductors TM must have their location chosen so as not to produce a false or improper restoration of the car apparatus while the train is in a caution block and a brake application must be maintained for the sake of safety. If it should happen to be necessary to locate the pair of inductors, such as TM, for enforcing a restricted speed limit for permanent hazards under clear traffic conditions at such a point as would interfere with the proper control of the train under caution traffic conditions, this pair of inductors may be provided with windings automatically placed on closed circuit under caution conditions and on open circuit under clear conditions, it being obvious that there is no need for the maximum speed limit provided by such pair under caution traffic conditions.

With respect to the particular advantages and value of this invention in its practical application to the automatic train control problem, the first feature of significance relates to the additional facility of train movement afforded with the same degree of safety. As outlined hereinbefore, it is assumed to be an established principle that any system of train control should be such that the engineer can not relax his vigilance or use any less care in watching for the signal indications and handling his train than if the train were not equipped with train control apparatus. It has already been proposed to maintain or assure such vigilance on the part of the engineer by imposing a penalty whenever an automatic application of the brakes occurs on account of excessive speed. In other words, whenever the train exceeds the "dead-line" curve of limiting speed, and an automatic operation occurs, the penalty is inflicted. According to this proposed scheme, it will be evident that the engineer is required to govern the speed of his train in conformity with such "dead-line" curves; but when it comes to establishing such a "dead-line" curve for all blocks, all grades, make-up of train, and other varying factors, it is found that it is frequently necessary for the engineer, in order to avoid the penalty, to govern the train in a peculiar

fashion and keep the speed much lower than actually required for safety. It may be explained that this is due to the difficulty of providing by a present known means, an ideal "dead-line" curve of limiting speeds for all points along the railroad and under all conditions; and this difficulty is found to a more or less degree in all known types of speed control systems, whether intermittently or continuously acting, whether of the point-to-point speed limit type, such as the time-distance interval system herein disclosed, or a continuing speed limit type employing a speed responsive device with either a gradual or abrupt change in speed limits.

With reference to the essentials of safety, however, it can be readily seen that it is proper for the train to exceed the speed limits arbitrarily established, provided the train is being slowed down with a brake application as effective and corresponding to that upon which the arbitrary speed limits are based. Obviously, it is immaterial whether this brake application be manual or automatic, so long as it is actually effective and will stop the train in time. Bearing these points in mind, it can be appreciated that the system of this invention, while it maintains the same vigilance and alertness of the engineer, permits the train to run safely at higher speeds than those arbitrarily prescribed by the automatic system, rather than compelling the train in every instance to keep below such arbitrary speed limits. A comparison of the performance curves 136 and 137 in Fig. 2, shows a typical instance of the saving of time and the additional facility of train movement afforded by this invention, as compared with the system where a penalty is inflicted every time the limiting speed limits are exceeded. Among other things, the additional facility in train movement is due to the possible decreased length of blocks. To illustrate, if the train is obliged to follow a performance curve such as indicated at 136, the brakes must be applied at some distance back of the first pair of inductors TP; and in strict conformity with the principles of block signals, it would follow that the signal Z would likewise have to be placed further back at the point where this brake application has to be started, thereby increasing the length of the block considerably more than braking distance for the maximum speed. The more restricted or inaccurate the speed limits provided by the system of automatic train control, the more the gain in facility by employing the principle of suppressed penalty characterizing this invention; and as a general statement, even in a system providing a very accurate curve of permissive or limiting speed, there are many blocks and many situations where there is a material saving in time and increase in track capacity.

Another advantageous feature of this in-

vention is that it facilitates and simplifies the handling of the train by the engineer. Instead of being required to estimate quite accurately the actual running speed and the varying speed limits permissible at different points, the engineer merely has to ascertain roughly that the speed is excessive and apply the brakes. To a large extent the engineer may run his train the same as he would without the train control equipment, governing his actions in accordance with the signal indications and locations. Such a procedure is considerably simpler and easier than trying to run to certain arbitrarily set speed limits.

To a certain extent, this invention gives additional safety. It must be recognized that automatic devices sometimes get out of order. If the engineer gets in the habit of depending upon the automatic equipment and waiting for action thereby, a dangerous condition may be created. With the arrangement of this invention, however, the engineer has no way of knowing when the apparatus is not functioning properly, and being penalized for failure to make a timely brake application, the engineer as a rule will always apply the brakes and stop the train safely, even though some part of the automatic control apparatus may be out of order.

It should also be understood that the penalty imposed does not interfere or prevent the handling of the train in the regular way. In the case of long freight trains, for example, where it may be desirable to "split" the reductions to adjust the slack, these split applications may be made without difficulty before exceeding the critical speed limits, it being observed that the suppression valve SV is responsive to a certain reduction in equalizing reservoir pressure, whether that reduction be made continuously in one stage or in two or more stages. Inasmuch as the critical speed limits are based upon a full service application immediately applied, it is evident that the "splitting" of applications should take place before these speed limits are exceeded, since this is the only way in which the train can be stopped safely, disregarding the inaccuracies of the permissible speed limits.

While the invention has been shown applied in Fig. 2 to a system employing a plurality of speed limit control points in a block, the same organization may be used with any number of speed limits. For example, there may be only one speed limit at the entrance to a block, or the pair of inductors may be so closely spaced as to give the equivalent of an automatic stop independent of speed. In fact, a simple automatic stop arrangement with or without overlap, may be used for certain portions of the railroad, and a more complete or refined system of speed control for other portions.

Modification of Fig. 3.—In the arrange-

ment of Fig. 1, hereinbefore explained, the reduction occurring upon an automatic application is limited by a manual action of the engineer in reducing equalizing reservoir pressure. It is considered that this arrangement is not objectionable, excessive reduction occurring only in the event of wilful neglect by the engineer, or if the engineer is incapacitated. The amount of brake pipe reduction occurring upon automatic application may, if desired, be automatically limited; and the modified construction of the application valve shown in Fig. 3 is designed, among other things, to perform this function.

This application valve of Fig. 3 is very similar in its construction and operation to that shown in Fig. 1 and already described, so that only the differences need be pointed out. The equalizing piston discharge valve 42 exhausts through pipe 48 and cavity 47 are direct to atmosphere, rather than under the control of the slide valve 52. The reservoir ER is connected by pipe 43 and cavity 44 to a pipe 45, the same as in Fig. 1; but the pipe 45 in Fig. 3, instead of connecting permanently and directly with the brake pipe, is connected to the brake pipe through an additional valve 140 on the electro-pneumatic valve 58, this valve 140 being open while the engineer's valve is in the running position and being closed in the other positions of the engineer's valve. In short, there is produced and trapped in the reservoir ER the normal running brake pipe pressure; whereas in Fig. 1, the pressure in the reservoir ER is that then existing in the brake pipe at the time of operation of the application valve, this pressure being perhaps less than normal due to a prior manual brake application.

A reduction reservoir RD is connected by pipe 141 and cavity 47 to atmosphere when the application valve is in the normal position; and this reduction reservoir RD is connected through restricted orifice 142, port 143 and cavity 44 to the equalizing reservoir ER when the application valve has operated. Thus, the normal brake pipe pressure trapped in the reservoir ER is expanded into the reduction reservoir RD, normally at atmospheric pressure, through a restricted opening corresponding approximately in size to the preliminary exhaust port in the regular engineer's brake valve. Consequently, pressure in the reservoir ER drops at a predetermined rate and to a predetermined value, namely, pressure at which pressure equalizes in the reservoirs ER and RD. It will be obvious that the resultant or equalization pressure, which determines the amount of brake pipe reduction, may be anything desired by proportioning the volumes of reservoirs ER and RD.

This modified construction shown in Fig. 3 operates in the same way as previously explained, with the exception that the applica-

tion valve makes a predetermined reduction in brake pipe pressure, determined by the respective volumes of the reservoirs ER and RD, independently of the suppression valve SV, and as a result, brake pipe pressure is limited upon automatic application irrespective of any action by the engineer.

A restricted orifice 142 is employed so as to reduce the pressure in the reservoir ER at approximately the same rate as the pressure drops in the regular equalizing reservoir, making it possible to vent the brake pipe in two places without exceeding the limited rate at which the brake pipe may be vented without throwing the triple valves into quick action and producing an emergency application which may be particularly objectionable on long freight trains.

While a specific type of speed control system has been disclosed in conjunction with this invention, and while the specific and particular form of means, partly pneumatic, and partly electrical, been disclosed for carrying out the functions of this invention, it will be evident that this particular disclosure is susceptible of considerable modification and adaptation without sacrificing the advantageous characteristics and features of the invention or departing from the spirit of the invention.

As a general proposition, this particular invention has reference to the suppression of penalty if the engineer actually controls the train safely by a brake application, so as to permit a predetermined speed limit being exceeded without penalty. In its broadest aspect, the invention is not limited to any particular means for communicating impulses from the trackway to the vehicle, such means being either intermittently acting or continuously acting; nor to any particular type of speed control system; nor to any of the specific organizations and arrangements of devices and circuits disclosed. I desire to have it understood, therefore, that the invention is not limited to the particular ways and means herein described and shown, but is susceptible of broad application so far as comes within the scope of the appended claims.

What I claim is:

1. In an automatic train control system for railroads, the combination with the air-brake equipment of a vehicle, of an automatic brake setting device acting on said equipment to produce a brake application of a predetermined effect, automatic apparatus on the vehicle controlled from the trackway in accordance with traffic conditions for causing operation of said device if the vehicle exceeds certain speed limits during its progress while dangerous traffic conditions exist ahead, said apparatus including control means which once operated remains in that condition until restored, manually operable means accessible

only from the ground for restoring said control means, and other means for permitting restoration of said control means and effective only if the engineer manually initiates a brake application prior to the operation of said brake setting device and thereafter maintains an effective brake application.

2. In an automatic train control system for railway vehicles equipped with an air-brake system, automatic apparatus on a vehicle for causing a brake application under predetermined conditions of traffic and speed, said apparatus when once operated continuing such brake application until restored, and means to restore said apparatus and permit the release of the brakes, said means being effective only if the engineer initiates a manual brake application prior to the automatic operation of said apparatus.

3. In a train control system, automatic brake control apparatus on a vehicle operated automatically dependent on traffic conditions and the running speed of the vehicle, said apparatus when once operated tending to bring the vehicle to a stop before the brakes can be released, and means effective only if the engineer manually applies the brakes prior to the automatic operation of said apparatus for permitting restoration thereof as soon as the speed of the vehicle has been reduced to a safe speed.

4. In a train control system, brake control apparatus, on a vehicle automatically operated dependent upon traffic conditions and the running speed of the vehicle to make a full service application, said apparatus causing such brake application each time the prescribed speed limits are exceeded irrespective of any action by the engineer, and means permitting restoration of said apparatus and release of the brakes after the speed has been reduced below the prescribed limits, provided that prior to the automatic operation of said apparatus the engineer manually initiated a brake application.

5. In a train control system, the combination with automatic brake control apparatus on a vehicle, of means operable only if a predetermined brake application is in effect, said means permitting restoration of said apparatus after the speed of the vehicle has been reduced to a safe limit but permitting said apparatus to operate each time the speed is excessive.

6. In a train control system of the general type described characterized by the automatic application of the brakes whenever the speed of the vehicle equipped with said system is excessive, penalty means requiring special action on the part of the engineer before the brakes can be released and the train proceed after each automatic brake application, and means for rendering said penalty means ineffective and permitting the train to proceed without such special action, said last

mentioned means performing its function only if prior to said automatic brake application the engineer initiates and completes an effective brake application.

7. In a train control system of the character described characterized by an automatic application of the brakes of a vehicle under dangerous traffic conditions and dependent upon the running speed of said vehicle, and further characterized by the imposition of a penalty upon the engineer for failure to initiate a manual brake application prior to such automatic brake application, the combination of automatic brake setting apparatus operable each time the speed is excessive and irrespective of any action by the engineer of means for suppressing said penalty only provided that the engineer initiates said manual brake application prior to the automatic operation of said apparatus.

8. In a system of automatic train control in which the vigilance of the engineer is maintained by imposing a penalty for failure to take appropriate action upon the occurrence of each automatic brake application, the combination with an automatic brake setting device acting upon the air-brake equipment of a vehicle to produce a substantially full service brake application, of means for suppressing said penalty without preventing operation of said brake setting device, said means being effective only if the engineer's brake valve is placed in the service position prior to the automatic operation of said device and kept there until a substantially full service brake application has been manually effected.

9. A train control system for railroads comprising, automatic apparatus on the vehicle dependent upon traffic conditions and the running speed of the vehicle for producing an automatic brake application of a predetermined effect, said apparatus operating each time traffic conditions and the running speed require, irrespective of any action on the part of the engineer, and automatic means for imposing the penalty on the engineer each time said apparatus operates unless prior to said automatic operation the engineer places his brake valve in the service position and maintains it there until a predetermined reduction has been made in the normal running pressure in the equalizing reservoir of the air-brake system.

10. A train control system for railroads comprising, automatic apparatus on the vehicle dependent upon traffic conditions and the running speed of the vehicle for producing an automatic brake application of a predetermined effect, said apparatus operating each time traffic conditions and the running speed require, irrespective of any action on the part of the engineer, penalty suppressing means if effective permitting restoration of said apparatus and release of the brakes.

as soon as the speed of the vehicle has been reduced to a safe speed, said apparatus being restorable to permit the brakes to be released independently of said penalty suppressing means only after the vehicle has been brought substantially to a stop, and means for rendering said penalty suppressing means effective only if prior to the automatic operation of said apparatus, the engineer's brake valve is in the service position and remains in that position or if there actually exists a predetermined reduction in the normal running pressure in the equalizing reservoir of the air-brake system.

11. A train control system for railroads comprising, automatic apparatus on the vehicle dependent upon traffic conditions and the running speed of the vehicle for producing an automatic brake application of a predetermined effect, said apparatus operating each time traffic conditions and the running speed require, irrespective of any action on the part of the engineer, a manually operable restoring device accessible only from the ground for restoring said apparatus, a penalty suppressing means, said apparatus being restorable to permit release of the brakes independently of said restoring device only if said penalty suppressing means is effective and automatic means for rendering said penalty suppressing means effective provided the engineer prior to the automatic operation of said apparatus places his brake valve in the service position and keeps it there until a predetermined reduction has been made in the normal running pressure in the equalizing reservoir.

12. In an automatic train control system, car-carried equipment comprising, an automatic brake setting appliance acting upon the air-brake system of the vehicle to produce a predetermined brake application, apparatus controlled from the trackway in accordance with traffic conditions for governing the operation of said appliance, a penalty suppressing means, and means for rendering said penalty suppressing means effective without preventing operation of said appliance provided the engineer manually applies the brakes prior to the operation of said appliance.

13. In a train control system of the character described in which a penalty for the engineer may be suppressed by appropriate action on his part without preventing the operation of the automatic brake setting means, the combination with means for suppressing said penalty, of means for rendering said penalty suppressing means effective only if the engineer's brake valve is in the service position, and other means for rendering said penalty suppressing means effective provided there actually exists a predetermined reduction in the normal running pres-

sure in the equalizing reservoir of the air-brake system.

14. In a train control system of the character described in which a penalty for the engineer may be suppressed by appropriate action on his part without preventing the operation of the automatic brake setting means, a penalty suppressing device, a circuit for rendering said devices effective having two branches in multiple, contacts in one branch operatively connected to the engineer's brake valve enclosed only if said brake valve is in the service position and a circuit controller in the other branch automatically closed only if and so long as there exists a predetermined reduction in the normal running pressure in the equalizing reservoir of the air-brake system.

15. In a train control system of the character described, the combination with an air-brake system, of a normally open circuit having two branches in multiple, means for closing one of said branches if the regular engineer's brake valve of the air-brake system is in the service position and for opening said branch if said brake valve is in any other position, and pneumatically operated circuit controlling means automatically closed provided there exists a predetermined reduction in the pressure in the equalizing reservoir of the air-brake system.

16. In a train control system of the type described, a penalty stick relay, the stick circuit for said relay having two branches in multiple, contacts in one branch connected to the regular engineer's brake valve and closed only if said valve is in the service position, circuit controlling means for closing the other branch providing the pressure in the regular equalizing reservoir of the air-brake system has been reduced to a predetermined extent, and automatic brake control apparatus having its restoration but not its initial operation dependent upon said penalty relay.

17. In a train control system for vehicles equipped with an air-brake system of the usual type, automatic brake-setting apparatus including an electro-pneumatic valve, a stick relay on the vehicle controlling said electro-pneumatic valve, and automatically de-energized at certain points along the trackway whenever the speed of the vehicle exceeds predetermined speed limits while passing said points, a normally open pick-up circuit for said stick relay, and means permitting closure of said circuit only if prior to the de-energization of said relay the regular engineer's brake valve of the air-brake system is in the service position.

18. Car equipment for train control systems comprising, in combination with an air-brake system of the usual type including an equalizing reservoir, circuit controlling means automatically operated by air pressure, and means

for supplying pressure to said circuit controlling means only if there exists a predetermined difference between the equalizing reservoir pressure and the normal running brake pipe pressure.

19. In an automatic train control system, car equipment for railway vehicles equipped with an air-brake system of the usual type comprising, an electrically controlled and pneumatically operated brake application valve acting upon said system to produce an automatic application of the brakes, a stick relay controlling said application valve, automatic means controllable from the trackway for deenergizing and maintaining deenergized said stick relay at predetermined control points along the track if the speed of the vehicle at the particular control point exceeds a predetermined speed limit, means permitting reenergization of said stick relay after the speed of the vehicle has been reduced to a predetermined minimum only provided that prior to the deenergization of said relay the engineer places his brake valve in the service position and keeps it there until an effective brake application has been produced.

20. In an automatic train control system for governing the movement of railway vehicles equipped with air brakes, a brake setting device on the vehicle operable to produce an automatic brake application, a stick relay on the vehicle controlling the operation of said device, trackway means at predetermined control points defining space intervals, a time element device on the vehicle controlling said stick relay, said trackway means acting automatically in cooperation with said time element device to cause deenergization of said relay whenever the vehicle takes less than a predetermined time in traveling over any one of said space intervals, a penalty relay on the vehicle, said apparatus being automatically restored at any one of said control points if the vehicle takes more than said time in traveling the space interval at that point provided said penalty relay is energized, and means for energizing said penalty relay, said means being effective only if a manual application of the brakes is initiated or completed prior to the deenergization of said stick relay.

21. An automatic train control system for governing speed of railway vehicles through the blocks of an automatic block signal system comprising, car equipment including apparatus for acting automatically upon the air-brake equipment of the vehicle and causing a brake application of predetermined effect whenever the vehicle exceeds successively lower speed limits during its progress through a block with a next block in advance occupied, said apparatus when once operated due to the exceeding of said speed limits continuing in operation and maintaining the brakes applied until restored, manually operable means

accessible only from the ground for restoring said apparatus, the operation of said restoring means constituting a penalty, a penalty suppression device on the vehicle, means partly on the vehicle and partly on the track for causing restoration of said apparatus at intermediate points in the block if the speed of the vehicle is then below the limit for that particular point and provided said penalty suppression device is then effective and means for rendering said penalty suppression device effective only if operated prior to the automatic operation of said apparatus, said last mentioned means requiring the engineer to put his brake valve in the service position and keep it there until a brake application of predetermined effect has been produced.

22. In a speed control system for railroads divided into track circuited blocks, brake control apparatus on a vehicle automatically set into operation near the entrance to a block if the next block in advance is occupied, said apparatus continuing in operation until restored, and means for restoring said apparatus after the speed of the vehicle has been reduced to a predetermined minimum provided that the engineer anticipates the automatic operation of said apparatus with an effective manual brake application.

23. Automatic train control equipment for railway vehicles having an air-brake system of the usual type comprising, an automatic brake control appliance adapted to act upon said air-brake system and produce a brake application of a predetermined value, said appliance if once set into operation continuing in operation until restored, speed responsive means driven from the wheels of the vehicle and a penalty relay co-acting to restore said appliance as soon as the speed of the vehicle has been reduced to a predetermined minimum provided said penalty relay is operated, and means for operating said penalty relay so long as the engineer's brake valve is in the service position or a predetermined brake application is in effect, said penalty relay being operable only by said means and only provided one of said means is effective prior to the automatic operation of said brake control appliance.

24. In a train control system, apparatus on trackway and on a moving vehicle cooperating under dangerous traffic conditions to produce an automatic brake application whenever the vehicle takes less than a predetermined time in traveling a predetermined distance, said apparatus when once operated continuing in that condition and maintaining the brakes applied until restored, manually operable means for restoring said apparatus only after the vehicle has been brought substantially to a stop, and means permitting restoration of said apparatus at predetermined speeds without requiring the stopping thereof, said last mentioned means being ef-

fective only if the engineer's brake valve is placed in the service position prior to the operation of said apparatus and is kept in that position until a predetermined reduction has 5 been made in the pressure in the equalizing reservoir of the air-brake system.

25. In a train control system of the character described, means for determining when a predetermined brake application has been 10 manually effected including a reservoir, an electro-pneumatic valve open when energized and closed when deenergized, a connection from the usual brake pipe to said reservoir controlled by said valve, and a circuit 15 for energizing said valve including contacts operated by the regular engineer's brake valve and closed only if said brake valve is in the running position.

26. A device for automatic train control 20 systems responsive to the existence of a manual brake application comprising, in combination with the usual air-brake equipment including an equalizing reservoir, a main reservoir and brake pipe, a pressure reservoir, 25 means connecting said pressure reservoir to the brake pipe only while the engineer's brake valve is in the running position, and means operable whenever pressure in the equalizing reservoir is lower than in said pressure reservoir 30 to a predetermined extent.

27. An appliance of the type described for use in connection with train control systems comprising, a reservoir and electrically operated means for connecting said reservoir to 35 the brake pipe of the usual air-brake system only while the engineer's brake valve is in the running position.

28. A device for train control purposes and 40 adapted to manifest the existence of a predetermined reduction in the normal running pressure of the equalizing reservoir of the usual air-brake system comprising, a casing, a piston within said casing having sealing ridges on both faces, gaskets cooperating with 45 said ridges to form an air-tight joint with the piston in either of its extreme positions, means for supplying pressure to one side of said piston corresponding to the normal running brake pipe pressure, means supplying pressure from the equalizing reservoir to the 50 other side of said piston, and a spring acting upon said other side of said piston, said spring being of such strength as to cause the piston to shift whenever there exists a predetermined difference between the equalizing reservoir pressure and the normal brake pipe 55 pressure.

29. In a train control equipment of the 60 character described, the combination with a reservoir in which the normal running brake pipe pressure is trapped, of a circuit controlling device operated by air pressure whenever the pressure in the equalizing res- 65 ervoir of the air-brake system is less than

said trapped pressure by a predetermined amount.

30. In a train control equipment for vehicles in combination with the usual type of air-brake system, automatic brake applying means including an electrically controlled and pneumatically operated brake application valve, said application valve when operated acting to vent a brake pipe through a passage including a portion of said valve, 75 and means dependent upon the pressure in the regular equalizing reservoir of the air-brake system for closing said passage through which the pressure from the brake pipe is vented while said application valve 80 is operating.

31. In a train control equipment for vehicles equipped with the usual type of air-brake system, automatic brake applying means including an electrically controlled 85 and pneumatically operated brake application valve, a reservoir connected to the brake pipe while said application valve is in its normal inactive position, a piston and discharge valve automatically venting the brake 90 pipe at a rate and to a value corresponding to the change in pressure in said reservoir, and a port of restricted area exhausting said reservoir to atmosphere when the application 95 valve operates, the size of said reservoir and said port being proportioned with respect to the regular equalizing reservoir and the preliminary exhaust port of the engineer's brake valve so as to produce a drop in pressure in said reservoir at the same rate as 100 the pressure drops in the regular equalizing reservoir with the engineer's valve in the service position.

32. In a train control equipment for vehicles equipped with the usual type of air-brake system, automatic brake applying means including an electrically controlled and pneumatically operated brake application valve, said application valve acting to vent the brake pipe at a predetermined rate 105 when operated and continuing in operation until restored, and means effective only with the engineer's brake valve in the release position for permitting restoration of said application valve.

33. Car equipment for train control systems comprising, an automatic brake setting appliance, a normally energized electro-pneumatic valve controlling said appliance and having contacts opened upon deenergization of said valve, an energizing circuit for said valve including its contacts and means for shunting said contacts when the engineer's brake valve is in the release position.

34. In an automatic train control system, 125 a brake setting appliance, means for operating said brake setting appliance dependent upon traffic conditions and the running speed of the train, means for restoring said appliance after operation thereof only after 130

a predetermined application of the brakes has been effected, and a signal indicating when such predetermined application has been made.

5 35. In a system of the character described, means operable only after a predetermined reduction has been made in the pressure of the regular equalizing reservoir of the air-brake system, and a signal indicating when 10 said reduction has been made.

36. A system of train control of the type described characterized by the automatic application of the brakes of a vehicle accompanied by a penalty, and means for suppressing said penalty without preventing such automatic brake application provided the engineer anticipates such automatic application by initiating a manual brake application.

37. In a train control system for governing 20 the movement of railway vehicles over tracks divided into blocks, car-carried apparatus and trackway means cooperating to produce an automatic application of the brakes of the car at any one of a plurality of points in a 25 block whenever the car passes said points at a speed higher than a predetermined speed limit for that point and the block next in advance is occupied by another train, and suppressing means on the car which may be 30 rendered effective by the engineer provided he initiates or completes a manual brake application prior to the automatic operation of said apparatus, said apparatus when once operated continuing in operation until restored and being automatically restored by 35 the trackway means at any one of said points only if the speed of the car at that time is below the speed limit for the particular point and provided said suppression means is effective.

38. Car equipment for train control systems comprising, an automatic brake setting appliance, a normally closed valve controlling said appliance and having contacts opened 45 upon the opening of said valve, and electrical means, controlled by the position of the regular engineer's brake valve, for shunting said contacts and closing said valve.

39. In an automatic train control system, 50 car-carried equipment comprising an automatic brake setting appliance acting upon the air brake system of the vehicle to produce a reduction in the usual brake pipe pressure, apparatus controlled from the trackway in 55 accordance with traffic conditions for governing the operation of said appliance, and means for limiting the reduction in brake pipe pressure only if the engineer's brake valve is manually moved out of the running 60 position.

40. A system of train control of the type described characterized by the automatic application of the brakes of a vehicle accompanied by a penalty when predetermined 65 speed limits are exceeded at given points

along the trackway under unfavorable traffic conditions, and means for suppressing said penalty without preventing such automatic brake application provided the engineer takes an appropriate action before said automatic application of the brakes is initiated.

41. In an automatic train control system, means for automatically applying the brakes of the vehicle and for subsequently imposing a penalty on the engineer whenever the vehicle passes certain control points at an excessive speed, and means for suppressing said penalty without preventing such automatic brake application provided the engineer performs a manual act before passing said control points at such speed.

42. Brake control apparatus for air brake systems of the type in which the brake pipe is normally charged and in which venting of the brake pipe effects a brake application, an engineer's brake valve for controlling the brakes by venting and charging said brake pipe, automatically operated brake applying mechanism controlled by suitable train control mechanism for venting said brake pipe, penalizing means which if actuated inflicts a penalty upon the engineer, means for preventing said penalizing means becoming active if either the engineer's brake valve is in a brake applying position or a brake application has been made manually and the engineer's brake valve assumes the lap position before said brake applying mechanism is operated, and means for preventing excessive venting of the brake pipe if the brake pipe is caused to be simultaneously vented by the engineer's brake valve and said brake applying mechanism.

43. In an automatic train control system including the apparatus of the usual normally charged train pipe type air brake system, the combination with automatic brake applying mechanism which if automatically operated by suitable train control mechanism applies the brakes by venting said train pipe through a vent so long as it remains in its operated condition, manually operable means for applying the brakes by venting said train pipe, and means for closing said vent upon a predetermined and limited reduction in train pipe pressure rendered effective if the brakes have been manually applied but not rendered effective if the brakes have been applied automatically only.

44. In an automatic train control system including the apparatus of the usual normally charged train pipe type air brake system, the combination with automatic brake applying mechanism which if automatically operated by suitable train control mechanism applies the brakes by venting said train pipe through a vent so long as it remains in its operated condition, manually operable means for applying the brakes by venting said train pipe, and means for closing said vent upon a pre-

determined and limited reduction in train pipe pressure rendered effective if the brakes are applied simultaneously manually and automatically but not closing said vent if the brakes are automatically applied only.

45. Automatic brake applying mechanism for applying the brakes of air brake systems of the type employing a brake pipe which is normally charged and which if vented causes an application of the brakes comprising, an equalizing discharge piston valve having a piston and an exhaust port and having both sides of the piston thereof normally connected to the brake pipe, a reservoir connected to the chamber above said piston, a passage connecting the exhaust port of said equalizing discharge piston valve leading from the chamber below said piston to atmosphere, and means separate from said equalizing discharge piston valve for closing said passage when the brake pipe has been vented to a predetermined extent.

46. Automatic brake applying mechanism for applying the brakes of air brake systems of the type employing a brake pipe which is normally charged and which if vented causes an application of the brakes comprising, an equalizing discharge piston valve having a piston and an exhaust port and having both sides of the piston thereof normally connected to the brake pipe, a reservoir connected to the chamber above said piston, a passage connecting the exhaust port of said equalizing discharge piston valve leading from the chamber below said piston to atmosphere, and separate means for closing said passage when an adequate manual brake application has been made.

47. Automatic brake applying mechanism for applying the brakes of air brake systems of the type employing a brake pipe which is normally charged and which if vented causes an application of the brakes comprising, an equalizing discharge piston valve having a piston and an exhaust port and having both sides of the piston thereof normally connected to the brake pipe, a reservoir connected to the chamber above said piston, a passage connecting the exhaust port of said equalizing discharge piston valve leading from the chamber below said piston to atmosphere, and separate means for closing said passage if an automatic brake application is anticipated by initiation of a manual brake application.

48. In an automatic train control system including the apparatus of the usual normally charged train pipe type air brake system, the combination with automatic brake applying mechanism which if operated by suitable train control mechanism applies the brakes by venting said train pipe and continues such venting so long as said brake applying mechanism is in its active condition, manually operable means for applying the

brakes by venting said train pipe, and reduction limiting means for limiting to a fractional extent only the reduction in train pipe pressure due to operation of said automatic brake applying mechanism, said reduction limiting means being rendered effective only if the automatic brake application is anticipated by the initiation of a manual brake application.

49. A system of automatic train control of the type described and characterized by the automatic venting of the brake pipe of a railway vehicle and an application of the brakes thereof accompanied by a penalty, and means for suppressing said penalty without preventing such automatic application by initiation a manual brake application, said penalty consisting of excessive venting of the brake pipe by the automatic application of the brakes when not anticipated by initiation of a manual brake application.

50. A system of automatic train control of the type described and characterized by the automatic venting of the brake pipe of a railway vehicle and an application of the brakes thereof accompanied by a penalty which consists in requiring a lapse of time before the brakes can be released, and means for suppressing said penalty without preventing such automatic brake application providing the engineer anticipates such automatic application by initiation of a manual brake application.

51. A method of stimulating the vigilance of the engineers of trains equipped with automatic train brake control mechanism; which consists in allowing the engineer himself to apply the brakes when an automatic brake application is about to be made by the automatic brake applying mechanism without interfering with the operation of such automatic mechanism; and in penalizing the engineer each time the automatic brake applying mechanism is operated, unless the operation of the automatic brake applying mechanism is anticipated by the engineer himself initiating a brake application.

52. A method of stimulating the vigilance of the engineers of railway trains equipped with automatic train control brake applying mechanism; which consists in penalizing the engineer each time the automatic brake applying mechanism is operated to effect a brake application, and in canceling such penalty without interfering with the operation of the automatic brake applying mechanism in the event the engineer himself starts a brake application before the automatic brake applying mechanism is operated and maintains the brakes applied.

53. Brake applying mechanism for air brake systems of the type in which a brake pipe is normally charged and in which venting of the brake pipe effects a brake application, an engineer's brake valve for manually

effecting venting of the brake pipe, pressure reduction responsive means operated if the brake pipe has been vented in response to manual operation of the engineer's brake valve to an extent a predetermined degree below the pressure which existed in the brake pipe when the engineer's brake valve was last moved from the running position, and audible means sounded in response to operation of said reduction responsive means.

54. Brake applying mechanism for air brake systems of the type in which a brake pipe is normally charged and in which venting of the brake pipe effects a brake application, an engineer's brake valve for manually effecting venting of the brake pipe, pressure reduction responsive means operated if the brake pipe has been vented in response to manual operation of the engineer's brake valve to an extent a predetermined degree below the pressure which existed in the brake pipe when the engineer's brake valve was last moved from the running position, and means for informing the engineer when such predetermined reduction has been made responsive to operation of said reduction responsive means.

55. In an air brake apparatus, a brake valve, a reservoir normally connected to the brake valve, a brake pipe, automatic means for opening said brake pipe to the atmosphere and closing the connection between said reservoir and brake valve, an electro-magnet controlling said means, and means for effecting restoration of said automatic means effective if the engineer's brake valve is moved to a brake application position and is then for a time moved to the brake releasing position.

56. In an automatic train control system including the apparatus of the usual normally charged train pipe type air brake system, the combination with automatic brake applying mechanism which if operated by suitable train control mechanism applies the brakes by venting said train pipe and continues such venting so long as said brake applying mechanism is in its active condition, manually operable means for applying the brakes by venting said train pipe, and reduction limiting means for limiting to a fractional extent only the reduction in train pipe pressure due to operation of said automatic brake applying mechanism but ineffective to wholly prevent an automatic brake application, said reduction limiting means being rendered effective only if the automatic brake application is anticipated by the initiation of a manual brake application.

60 In testimony whereof I hereby affix my signature.

NEIL D. PRESTON.
